UNITED STATES PATENT OFFICE

MAE JOSEPH, OF BROOKLYN, NEW YORK, ASSIGNOR TO PARK & TILFORD, OF NEW YORK, N. Y., A CORPORATION OF NEW YORK

DESIGN FOR A BOTTLE

Application filed March 29, 1932. Serial No. 43,319. Term of patent 3½ years.

To all whom it may concern:

Be it known that I, MAE JOSEPH, a citizen of the United States, residing at No. 196 Rockaway Parkway, in the borough of Brooklyn, county of Kings, and State of New York, have invented a new, original, and ornamental Design for a Bottle, of which the following is a specification, reference being had to the accompanying drawings, forming part thereof:

Fig. 1 is a front view showing my bottle; Fig. 2 is a long side view showing my bottle, and

Fig. 3 is a top view showing my bottle.

I claim:

The ornamental design for a bottle as shown.

MAE JOSEPH.
